N. M. LOWER.

SCREW CONVEYER.

APPLICATION FILED FEB. 24, 1919.

1,373,748.

Patented Apr. 5, 1921.

UNITED STATES PATENT OFFICE.

NATHAN M. LOWER, OF PITTSBURGH, PENNSYLVANIA, ASSIGNOR TO LOCOMOTIVE STOKER COMPANY, OF PITTSBURGH, PENNSYLVANIA, A CORPORATION OF PENNSYLVANIA.

SCREW CONVEYER.

1,373,748.

Specification of Letters Patent.

Patented Apr. 5, 1921.

Original application filed August 1, 1918, Serial No. 247,762. Divided and this application filed February 24, 1919. Serial No. 278,916.

To all whom it may concern:

Be it known that I, NATHAN M. LOWER, a citizen of the United States, and resident of Pittsburgh, county of Allegheny, and State 5 of Pennsylvania, have invented certain new and useful Improvements in Screw Conveyers, of which the following is a specification, and which are illustrated in the accompanying drawings, forming a part thereof.

10 The invention relates to screw conveyers especially adapted for use in connection with locomotive stokers and herein shown and described as being applied to mechanism of that character.

15 It is common practice for the fuel to be transferred from the tender to the locomotive by means of a screw conveyer working in a trough and conduit located below the tender floor and delivering to a chambered 20 body carried by the locomotive, from which it is elevated by one or more similar screws. It is important to the efficient working of the elevating screws that the fuel be under pressure as it is taken up and carried forward by them, thereby reducing the frictional action upon it of the vane of the elevating screw. It is, nevertheless, desirable 25 that there be a free movement of the fuel in the horizontal or transferring conduit.

30 Again, it is desirable that the passage through which the fuel is moved be free from obstructions, such as journal bearings for the screw, and it is known practice to have the screw rotate freely in the conduit.

35 The object of this invention is to secure the various advantages above referred to, and also to provide for an improved bearing for the screw within the conduit.

40 An exemplification of the invention is illustrated in the accompanying drawings, which show a detail sectional view through adjacent portions of a locomotive and its tender, and show the conveyer in longitudinal 45 section.

This application is a division of my pending application filed August 1st, 1918, Serial No. 247,762.

50 The underframing of the rear end of a locomotive is represented at 1, and the forward end of the locomotive tender at 2. The deck floor of the locomotive cab is shown at

3, and the floor of the tender at 4. At 5 there is shown an elevator conduit, within which is housed an elevating screw 13 for 55 carrying fuel upwardly to be delivered to the fire-box of the locomotive, and at 6 a box or chambered body for receiving fuel from the transferring conveyer and from which box the elevator leads.

60 A transferring conduit 7 is located below the floor of the tender, and is flexibly connected with the receiving box 6 by means of a form of ball and socket joint, shown at 8, and a link 9.

65 Within the conduit 7 is located a screw conveyer, generally designated by the numeral 10. This screw may be driven by any suitable means, not shown, applied to its rearward end. At its forward end the screw 70 is rotatably supported upon the floor of the conduit 7, upon which the last turn 11 of its vane rests. The various turns, as 12, of the screw vane to the rear of the turn 11 are of less radial width than the latter, and hence 75 have less carrying capacity and are not called upon to support the conveyer screw. The turn 11 of the vane is also widened or thickened, in axial direction, to give it a broad bearing surface for engagement with the 80 bottom of the conduit.

78 The screw 10 carries the fuel forwardly in the trough as a somewhat loose mass. As the material reaches the more contracted portion of the trough where it joins the box 6, it is 85 taken up by the larger turn 11 of the screw and forced into the box with increased pressure. This pressure assists the elevating screw by effectively reducing the frictional resistance of the fuel thereon and checking 90 a tendency of the column of ascending material to merely rotate in the elevating conduit. This increased capacity of the last turn 11 of the transferring screw also prevents a retardation of the fuel at the delivery end of the conduit which, should it occur, would cause the material to pile up at the forward end of the trough and overflow its walls.

95 The wide face of the supporting turn 11 100 of the screw provides adequate bearing surface and prevents undue wear of the parts.

I claim as my invention—

1. In a locomotive stoker, in combination,

a fuel-transferring screw having its final turn of greater radius than the remainder of its turns, and fuel elevating screw means receiving from the transferring screw.

5 2. In a locomotive stoker, in combination, a conduit for transferring fuel from the tender of the locomotive, a receiving cham-

ber on the locomotive into which the conduit discharges, a screw conveyer in the conduit, the delivery end of the screw being of 10 greater carrying capacity than the remaining portion thereof, and fuel elevating screw means leading from the receiving chamber.

NATHAN M. LOWER.
